ELECTRICAL REGULATOR

John J. Root, New York, N. Y.

Application October 4, 1945, Serial No. 620,281

2 Claims. (Cl. 201—62)

1

This invention relates to electrical regulating apparatus, and more particularly to a device designed to stabilize the output of an electrical system.

Many forms of voltage regulators or controls are known to the art. One of these is a vibrator type of regulator which operates by virtue of an electromagnet arranged for vibrating co-action with a contact. The contact serves to periodically interpose a resistance in the circuit, the vibration of the contact thus effecting a decrease of the average current value. While my invention lends itself to an environment wherein such voltage regulators are found, it will be apparent from the description to follow that the improvement set forth herein is applicable to a wide variety of systems and conditions wherein voltage or even frequency variations must be automatically corrected.

One of the objects of this invention is to provide an efficient regulator for correcting deviations from a standard reference level, such as may be applicable to automatic voltage regulators.

Another object of this invention is to produce a mechanical movement in response to an electrical stimulus, which movement will serve to change the electrical circuit characteristics and neutralize the stimulus so that the circuit is automatically stabilized by the action of the mechanical element. Allied with this object is a provision of such a device wherein the mechanical movement is highly amplified in relation to the stimulus that produces it. In this way a slight deviation from regularity can be detected and neutralized efficiently by virtue of the amplified and neutralizing motion it produces. Accordingly, a circuit for voltage or frequency regulation or the like may be provided wherein a minimum of physical movement may be required to control a substantial change in the value of an electrical component.

Another object of this invention is to provide a voltage regulator circuit, which shall be capable of handling large values of electrical current, and further, wherein no vibration, buzzing, or constant mechanical motion attends the operation of the device.

Still another object of this invention is to produce a mechanical movement for altering the characteristics of an electrical circuit wherein the sensitivity of the device may be easily regulated so as to control the extent of said movement and the effect thereof on the circuit.

Other objects of my invention will be apparent in the following description, it being understood

2

that the above general statement of the objects of my invention are intended to describe and not to limit it in any manner.

Referring to the drawings:

5 Fig. 1 is a side view of the apparatus in elevation.

Fig. 2 is a section along the line 2—2 of Fig. 1, viewed as indicated by the arrows.

10 Fig. 3 is a section along the line 3—3 of Fig. 2.

Fig. 4 illustrates schematically an electrical circuit embodying the invention disclosed herein.

Fig. 5 is a schematic view illustrating the rocking movement of the regulating element.

15 Fig. 6 is a plan view of a capacitor element used in a modified embodiment of the invention.

The apparatus includes a supporting frame 10 of electrically insulating material upon which the components of the apparatus may be mounted. Supported on frame 10 are a pair of resistance elements 11 and 12 which are maintained in an upright position by means of the stand-off insulators 13 and 14, suitable bolts 15 serving to secure these elements together.

20 Resistance elements 11 and 12 may be made of any commercial type of electrical resistive material, such as the well known Nichrome. These resistive elements may be provided with off-set ends 16 and 17 so that incorporation in a suitable circuit is facilitated, as illustrated in Figure 4.

25 An arcuate member 18 is arranged to rock upon the resistance elements 11 and 12 jointly so as to bridge these resistance elements along progressively varying lengths thereof, depending upon the rocking motion of the arcuate member 18.

30 It will be apparent that as arcuate member 18 is rocked so that its top end abuts the resistance elements, the electrical resistance between points 16 and 17 will be increased due to the increased length of the elements which are caused to be

35 in an electrically series relationship by the bridging effect of the arcuate member 18. Arcuate member 18 is, of course, of electrically conductive material such as copper or silver, or any other suitable material. On the other hand, when 40 arcuate member 18 is caused to rock in the opposite direction so that correspondingly decreased lengths of resistance elements 11 and 12 are incorporated in the series relationship, a lower resistance is produced.

45 The action of the arcuate member 13 in accomplishing the above mentioned resistance variations is schematically shown in Figure 5, the full lines thereof indicating the position of the arcuate member where higher resistance is accomplished and the dotted lines indicating

its position after being rocked so as to produce a lower resistance. It is, of course, unnecessary that both elements 11 and 12 represent electrical resistances, since should only one of these represent a resistance, the same effect would be achieved although in more gradual resistance variations.

Actuating means for arcuate member 18 are disposed at the ends thereof. The wire or rod 19 is connected to bracket 20 at the top end of arcuate member 18. It will be apparent that by pulling rod 19, arcuate member 18 will be caused to rock in a direction toward the top of the resistance elements. A similar rod or wire 21, connected to a bracket 22 secured to the lower end of arcuate member 18, is arranged to produce a counterforce tending to rock the arcuate member 18 in the opposite direction or in the direction of lowered resistance. A spring 23 having one terminal thereof connected to the frame 10, has its other terminal connected to the wire 21 so that the action of the spring 23 is to maintain the apparatus in the low resistance state. Means for producing a pulling force upon wire 19 is afforded by armature 24 of electromagnet 25. Electromagnet 25 is connected to frame 10 as by bolts 26. The usual flux producing winding 27 is provided on the electromagnet 25.

The armature 24 is pivoted at 28 to the core of the electromagnet and spring 29, connected at one of its terminals to the frame 10, serves to maintain armature 24 in an outward position relative to the electromagnet so that the arcuate member 18 is maintained in a position of rest or balance depending upon the relative strengths of springs 23 and 29. If desired, suitable stop means may be provided on electromagnet 25 to limit the outward movement of armature 24. It will be understood that wires 19 and 21 work in opposition, actuation for each wire being supplied respectively by the armature 24 and spring 23.

In order to avoid slippage of the arcuate member 18 which would produce a longitudinal movement thereof in a manner other than by rocking, a toothed rack 30 is arranged to mesh with an arcuate bracket 31 secured to the arcuate member 18. Thus, rocking motion of the arcuate member 18 will effect engagement of the respective teeth of the meshing members so that whereas rocking motion will be permitted, relative sliding will be prevented. It will be apparent that the function of rack 30 may be realized by various other mechanical devices such as curved guiding means designed to maintain the ends of arcuate member 18 in a particular path.

The apparatus above described is adapted to be incorporated in an electrical circuit through the leads 32 and 33 of electromagnet 25. In the event of an increase in voltage in the circuit, armature 24 will be attracted by the increased flux so as to rock arcuate member 18 toward a higher resistance condition. Thus additional resistance is injected into the circuit until the increased resistance balances the circuit voltage gain. Should the voltage decrease, the attraction of armature 24 will be accordingly relaxed and a lowered value of resistance will be incorporated in the circuit. Thus, the apparatus provides automatic regulation which responds to an electrical stimulus produced through an abnormal condition in the circuit.

An important feature of this invention is that slight movement of either rod 19 or 21 pro-

duces a considerable amplified action of the arcuate member 18 insofar as the longitudinal changes in bridging action is concerned. The degree of amplification of this mechanical movement depends upon the radius of curvature of arcuate member 18. A lower degree of curvature provides higher amplification so that minute movements of the controlling wires are considerably enhanced and the sensitivity of the device improved accordingly.

It will further be noted that the mechanical sensitivity can be decreased as desired by merely varying the point at which wires 19 or 21 are connected to arcuate member 18. By connecting these wires inwardly, or toward each other, the degree of amplification of the mechanical movement is decreased.

Means of rendering the resistance changes more effective are provided as shown in the schematic circuit diagram of Fig. 4, wherein the resistance elements 11 and 12 are incorporated in an electrical link 34, such as may be employed in many types of electrical circuits.

Transformer 35, which may be the input power transformer of a power supply, is provided with a step-down secondary 36 forming one end of the link 34, while transformer 37 is provided with a similar step-down winding 38 forming the other end of the link 34. Arcuate member 18 is shown schematically as a dotted line, serving to bridge the resistance elements. It will be apparent to those skilled in the art, that link 34 will have flowing therein electrical energy of low voltage and high current relative to the primary of input transformer 35. Since the extent of voltage changes produced by variations in resistance depend upon the amount of current flowing in the circuit, the compensating effects of any resistance variations produced by the rocking of arcuate member 18, will be amplified to a degree proportional to the step-down ratio of transformer 35. Winding 38 in link 34, together with step-up winding 37, serves to restore the original voltage-current relationship. Thus, the resistance variations are provided with an environment where they will have the most effect.

It is also to be observed that a stepless method of resistance injection is thus made practical by virtue of the reduced size of the resistance elements, which is made possible by the current transformation. Such stepless operation is a highly desirable objective for many reasons among which are the elimination of chattering when the degree of compensation required can only be obtained by a resistance value between two steps.

While I have described the above apparatus in relation to a voltage regulating system through compensating resistances, it will be apparent that inductances may be used. Furthermore, the benefits of the invention may be realized with the use of only one resistance element 11, wherein the arcuate member 18 serves as the movable arm of a potentiometer, the essential concept residing in the rocking of a co-acting element.

The device illustrated herein may be utilized for the compensation of frequency instability. In such an adaptation, resistance element 11 and 12 will be dispensed with and a capacitor element 39 such as illustrated in Fig. 6 may be used. The capacitor element 39, being triangularly shaped, exhibits a progressive change of capacitative function along the length thereof. Thus rocking of arcuate member 18 adjacent, but not touching capacitor element 39 as was done in the previous embodiment, forms a variable condenser the over-

all capacity of which depends principally upon the portion of capacitative element 39 which is brought into capacitative relationship with arcuate member 18 according to the rocking movement thereof. It is realized that the diverging end of arcuate member 18 from the element 39 retains capacity effect, during rocking action, but such effects are negligible in comparison to the capacity which is attained through the close relationship of the condenser elements at the area of co-action. The frequency control adaptation may be utilized through a conventional discriminator circuit such as used in frequency modulation systems whereby deviation from correct frequencies in either direction will produce a voltage of a particular polarity. Springs 29 and 23 in the apparatus, in cooperation with a normal voltage applied to winding 27 of electromagnet 25, may serve to maintain arcuate member 18 in a normal position so that the voltage output of the discriminator will add or subtract from the normal voltage so as to produce corresponding and compensating movement of arcuate member 18.

If desired, another electromagnet may be added to the lower end of the arcuate member 18, and any type of uni-directional current device such as a rectifier may be included in each electromagnet circuit so that each electromagnet would respond according to the polarity of the discriminator output.

I have shown a preferred embodiment of my invention, but it is obvious that numerous changes and omissions may be made without departing from its spirit.

35

I claim:

1. An electrical regulating instrument comprising a pair of elongated resistance elements each having a progressively higher electrical resistance in proportion to length, an arcuate member adapted to rock over and to co-act with the surfaces of said pair of resistance elements so as to bridge said resistance elements along progressively varying lengths thereof during said rocking action said varying lengths being continuously variable resistance areas of said elements, said arcuate member being of electrically conductive material so that said resistance elements are joined thereby in an electrical series relationship, spring means connected to one end of said arcuate

50

member for rocking said arcuate member toward one end of said pair of resistance elements, and electromagnet means connected to the other end of said arcuate member for rocking said arcuate member toward the other end thereof against the action of said spring means, and means to energize said electromagnet.

2. An electrical regulating instrument comprising a pair of elongated resistance elements each having a progressively higher resistance in proportion to length, an arcuate member adapted to coact with the surfaces of said pair of resistance elements by rocking thereupon so as to bridge said resistance elements along progressively varying portions thereof during said rocking action said varying lengths being continuously variable resistance areas of said elements, said arcuate member being of electrically conductive material so that said resistance elements are caused thereby to be in an electrical relationship for incorporation in an electrical circuit, spring means connected to one end of said arcuate member for rocking said arcuate member toward one end of said pair of resistance elements and electromagnet means connected to the other end of said arcuate member for rocking said arcuate member toward the other end thereof against the action of said spring means, said electromagnet being adapted to be incorporated in said circuit so as to be energized thereby, whereby increased current flowing in said circuit causes additional energization of said electromagnet and causes said arcuate member to rock toward said other end of said pair of resistance elements.
